UNITED STATES PATENT OFFICE

161,777

STAND FOR AN EMBOSSED MACHINE

William Richard Harding Moon, London, England, assignor to Adrema Limited, London, England, a British company

Application November 16, 1949, Serial No. 6,080
In Great Britain October 6, 1949

Term of patent 14 years

(Cl. D54—14)

To all whom it may concern:

Be it known that I, William Richard Harding Moon, a British subject, residing at London, England, have invented a new, original, and ornamental Design for a Stand for an Embossing Machine, of which the following is a specification, reference being had to the accompanying drawing, forming part thereof.

Fig. 1 is a perspective view showing the top, front and one side of a stand for an embossing machine, embodying my new design; and

Fig. 2 is a perspective view showing the top, rear, and other side thereof.

I claim:

The ornamental design for a stand for an embossing machine, as shown.

WILLIAM RICHARD HARDING MOON.
